MANFOLDING MACHINE

Frank Ronald Ford, Sparkbrook, Birmingham,
England, assignor to Frank R. Ford Limited,
Birmingham, England

Application September 5, 1939, Serial No. 293,519
In Great Britain September 30, 1938

7 Claims. (Cl. 101—132.5)

This invention relates to manifolding machines in which a copy sheet and a master sheet bearing in reversed script the matter to be produced are passed in pressure contact between a pair of rollers, the leading edge of said master sheet being secured to one of said rollers (hereinafter termed the cylinder) and said copy sheet being moistened before contact therewith.

The invention has particular reference to machines of the type described in Letters Patent No. 1,982,071, issued November 27, 1934, to Alfred Oser. In such machines, the spindle of the second roller (hereinafter termed the pressure roller) is supported in bearings which are slidably mounted on the machine frame, these bearings being operatively connected to crank arms on a shaft which can be oscillated to move the pressure roller out of contact with the cylinder whenever it is desired to attach a master sheet to the latter.

The moistening of the copy sheet is effected, in machines of the type aforesaid, by means of a stationary moistening pad extending transversely of the machine and against which the copy sheet is pressed by means of a pressing member carried by pivoted levers, such levers being oscillated so as to raise said pressing member at a predetermined point in the rotation of the cylinder to enable a fresh copy sheet to be fed to the nip between the cylinder and the pressure roller.

To indicate to the operator of the machine the precise moment at which a copy sheet should be fed to the nip for correct register with the master sheet, it is usual to provide automatic means whereby the cylinder is checked or momentarily stopped once in each revolution.

The chief object of the present invention is to provide improved means for effecting individual adjustment of the pressures exerted on the cylinder by the ends of the coating roller when the latter is in engagement therewith, and also for effecting the raising of the pressing member in relation to the stationary moistening pad.

Referring to the drawings—

Figure 1 is a side elevation of a duplicating machine embodying the present invention.

Figure 2 is a part-sectional plan view of the same.

Figure 3 is a view corresponding to Figure 1, but taken from the opposite side of the machine.

Figures 4 and 5 are sections on the lines 4—4 and 5—5, respectively, of Figure 2.

Figure 6 is a sectional side elevation, to an enlarged scale, of the cylinder of the machine.

In the construction of duplicating machine illustrated, the general arrangement of the apparatus is similar to that described in Letters Patent No. 2,048,543, issued to me July 21, 1936.

5 The frame of the machine comprises sheet metal side plates 10 secured together in spaced relationship by suitable tie-rods 11 and also by end plates 12 and a base plate 13 which are attached to marginal flanges 14 on the side plates 10 so that a box-like structure is produced.

Mounted between the side plates 10 and extending transversely of the machine is disposed an impression cylinder 15 having means for attaching thereto one edge of a master sheet 16. 15 Preferably this cylinder 15 is constructed from a length of seamless tube which is closed at its ends by flanged sheet metal discs 17 welded or otherwise secured in place. A supporting shaft 18, which is journaled in the side plates 10, 20 passes centrally through these end discs 17 and is riveted at 19 to sleeves 20 having peripheral flanges 21 which are attached to said discs.

The attachment of the master sheet 16 to the cylinder 15 is effected by means of a mechanical 25 clamp which may operate substantially as described in my prior patent aforesaid.

The cylinder 15 is formed with a longitudinal slot 22, immediately adjacent which there is disposed, within the cylinder 15 and extending 30 along the length thereof, a clamping member 23 journaled in the end discs 17.

This clamping member 23 takes the form of a rod which is longitudinally slotted or grooved at 24, and one end of which projects through 35 the adjacent end disc 17 of the cylinder 15, this projecting end having fixed thereto an actuating member 25 which may be oscillated to bring the slot or groove 24 in the clamping member 23 into or out of register with the cylinder slot 22. 40 The actuating member 25 locates the member 23 against axial movement in one direction, whilst movement thereof in the other direction may be prevented by a washer 26 which is secured to the opposite end of the member 23 by a screw 45 27 and engages the adjacent end disc 17.

In one position of the clamping member 23, the leading edge of a master sheet 16 may be passed through the cylinder slot 22 into the slot or groove 24 of the member 23, and may then be 50 clamped by partially rotating the latter. The actuating member 25 associated with the clamping member 23 conveniently comprises a collar having marginal lugs or projections 28 which facilitate its movement by hand, the edge of 55 the collar having angularly spaced notches 29

therein which are engageable by a spring detent 30 to define the two extreme positions of the clamping member 23.

Above the cylinder 15 and parallel thereto is mounted a pressure roller 31, the spindle 32 of which is journaled at its ends in bearings which are slideable on the side plates 10 of the machine so that the pressure roller 31 can be moved towards or away from the cylinder axis.

Each of these bearings may comprise a block 33 mounted in a suitable guide 34 on the adjacent side plate 10 and attached to each such block 33 at its upper end is a screw-threaded rod 35 extending longitudinally of the direction in which the block 33 is slideable.

By means of these screw-threaded rods 35 the bearing blocks 33 are operatively connected to crank arms 36 on a rock shaft 37 disposed transversely of the machine, at one side of and above the pressure roller 31, each such crank arm 36 preferably being arranged adjacent the inner face of the adjacent side plate 10 in which the rock shaft 37 is journaled.

An operating lever 38 is also secured to the rock shaft externally of the side plate 10, the arrangement being such that, by oscillation of this handle 38, the roller 31 can be brought into pressure contact with the cylinder 15 or raised therefrom to allow attachment of the master sheet 16 to the latter.

The operating lever 38 is adapted to be retained in at least one of its extreme positions (for example, in the position to which it has to be moved to bring the roller 31 into contact with the cylinder) by means of a spring-pressed ball or other detent 39 carried thereby and arranged to co-operate with a recess 40 in a plate 41 on the exterior of the machine. Preferably the detent 39 and its spring 42 are mounted within a handle 43 associated with the operating lever 38, but it will be understood that the arrangement may be reversed if desired and the detent 39 carried by the side plate 10 of the machine. A second recess may be provided if desired, to define the other extreme position of the lever 38.

Each of the screw-threaded rods 35 passes through a clearance hole 44 in the adjacent crank arm 36. An adjusting nut 45 is mounted on each threaded rod 35 below the associated arm 36, said nut, when screwed up, exerting pressure on the latter through the medium of an interposed helical compression spring 46 which encircles the rod 35. The nut 45 may be locked in its adjusted position by a second nut.

Alternatively, an arrangement similar to that described in my prior Patent No. 2,048,543 may be employed. That is to say, the threaded rod 35 may extend through a crank-pin associated with the arm 36, the end of which is forked to accommodate the rod 35. The latter may pass with clearance through a diametrical hole in the crank-pin, whose extremities are rotatably supported in the forked end of the arm 36.

Further nuts 47 are provided on the threaded rods 35 above the crank arms 36, which latter are pressed against these nuts 47 by the springs 48. The upper faces of the arms 36 may be curved as shown, so that the rods 35 shall be substantially normal to such surfaces during angular movement of the rock shaft 37.

The springs 46 on the threaded rods 35 ensure a resilient pressure between the roller 31 and the cylinder 15 when the two are brought into contact by oscillation of the crank arms 36 along 70

with the rock shaft 37, and the nuts enable such pressure to be regulated as desired. The provision in this manner of independent adjusting means at the opposite ends of the roller spindle 32 enables the pressure at the ends of the roller 31 to be controlled individually.

Also arranged between the side plates 10 of the machine is a tank 48 holding a moistening fluid which is fed by wicks 49 to a moistening pad 50 in a carrier 75 formed integrally with or attached to the tank 48.

This tank 48 is supported on the side plates 10 by means of screws 51 which engage threaded sockets 52 in opposite sides of the tank 48 and each of which rests in a hollow boss 53 inside the adjacent side plate. The screws 51 may carry lock nuts 54 adapted to engage the inwardly projecting bosses 53.

The pad carrier 75 comprises a bracket whose free edge is disposed adjacent the nip between the cylinder 15 and the pressure roller 31 and which rests on a rigid support, the latter being conveniently constituted by one of the tie-bars 11 connecting the side members of the frame.

Above the moistening pad 49 is a pressing member 55 extending transversely of the machine, the ends of this member being carried by a pair of levers 56 which are pivotally mounted on the side plates 10.

Normally the pressing member 55 is raised above the moistening pad 50 to enable a copy sheet 57 to be fed to the nip between the cylinder 15 and pressure roller 31 a pile of such sheets being carried by a suitable table 58 arranged at one end of the machine. Rotation of the cylinder 15, however, is arranged to effect the lowering of the pressing member 55 on to the moistening pad 50.

The pressing member 55 is maintained in its normal raised position by means of cams 59 engaging the levers 56 which carry said member, these cams 59 being at or adjacent the ends of a rock shaft 50 extending transversely of the machine and parallel to the common axis of the levers 56.

When the pad carrier 75 is supported upon a transverse tie-bar 11 of the machine as aforesaid, the rock shaft 60 may comprise a tube mounted on such bar 11 and preferably cut away as at 61 to allow the pad carrier 75 to rest on the latter. Alternatively, the rock shaft 60 may itself act as the support for the pad carrier 75.

At one end of the rock shaft 60 is fixed an arm 62 which extends downwardly therefrom adjacent the inner face of the side plate 10 and at the end of this arm 62 is a pin 63 (preferably carrying a roller 64) which projects through an arcuate slot 65 in the side plate 10.

One end of the shaft 18 on which the cylinder 15 is mounted projects through this side plate 10 and carries a crank handle 66 whereby the cylinder 15 may be rotated, a cam surface 67 on this handle co-operating, at each revolution of the latter, with the projecting pin 63, or roller 64 aforesaid.

Means are provided for checking or momentarily stopping the rotation of the cylinder 15 when the angular position of the clamping member 23 thereon with reference to the cylinder axis is such that a copy sheet fed to the nip between the pressure roller 31 and cylinder 15 will register correctly with a master sheet 16 clamped to the latter. As illustrated, such means comprise a spring-controlled detent 68 mounted in a housing 69 associated with the handle 66 and adapt-

ed to co-operate with a recess 70 in a plate 71 attached to the adjacent side of the machine.

The cam surface 67 on the crank handle 66 makes contact with the projecting pin 63 or roller 64 just prior to the checking of the cylinder 15 as above described, so that, as the spring-controlled detent 68 or other means comes into operation to check the cylinder, the rock-shaft 60 is oscillated and the cams 59 thereon raise the pressing member 55 clear of the moistening pad 50 ready for the insertion of a copy sheet 57.

If rotation of the crank handle 66 is then continued, the cam surface 67 thereon will ride past the pin 63 or roller 64 aforesaid and the springs 72 acting on the pressing member 55 will bring the latter down upon the inserted copy sheet 57 so as to press it against the moistening pad 50.

The cam surface 67 may be provided on a hardened finger 73 which is secured to the inner side of the handle 66, the end of such finger preferably being rounded or bevelled so as to slip easily past the projecting pin 63 or roller 64 of the moistening mechanism. Alternatively, the cam surface 67 may be formed on an integral part of the handle 66.

The copy sheets, on delivery from the machine may pass in known manner down a chute 74 at the end remote from the feed table 58.

What I claim then is:

1. A manifolding machine comprising a stationary frame, a rotatable cylinder, means for attaching a master sheet to said cylinder, a roller co-operating with said cylinder and adapted to bring a moistened copy sheet into pressure contact with the master sheet on said cylinder, bearings supporting the ends of said roller and mounted on said frame for sliding movement towards or away from said cylinder, an oscillatable shaft carried by said frame, crank arms fixed on said shaft, screw-threaded rods carried by said bearings and extending through openings in said crank arms, nuts screwed on said rods and co-operating with the sides of said crank arms nearest said bearings to enable individual adjustment of the pressures exerted on said cylinder by the ends of said roller.

2. A manifolding machine comprising a stationary frame, a rotatable cylinder, means for attaching a master-sheet to said cylinder, a roller co-operating with said cylinder and adapted to bring a moistened copy sheet into pressure contact with the master sheet on said cylinder bearings supporting the ends of said roller and mounted on said frame for sliding movement towards or away from said cylinder, an oscillatable shaft carried by said frame, crank arms fixed on said shaft, screw-threaded rods carried by said bearings and extending through openings in said crank arms, nuts screwed on said rods and co-operating with the sides of said crank arms nearest said bearings to enable individual adjustment of the pressures exerted on said cylinder by the ends of said roller, compression springs interposed between said nuts and the crank arms co-operating therewith.

3. A manifolding machine comprising, a stationary frame, a rotatable cylinder, means for attaching a master-sheet to said cylinder, a roller co-operating with said cylinder and adapted to bring a moistened copy sheet into pressure contact with the master sheet on said cylinder, bearings supporting the ends of said roller and mounted on said frame for sliding movement towards or away from said cylinder, an oscillatable

shaft carried by said frame, crank arms fixed on said shaft, screw-threaded rods carried by said bearings and extending through openings in said crank arms, nuts screwed on said rods and co-operating with the sides of said crank arms nearest said bearings to enable individual adjustment of the pressures exerted on said cylinder by the ends of said roller, abutments provided on said rods at the sides of said crank arms remote from said bearings, compression springs resting on said nuts and acting to press said crank arms against said abutments.

4. A manifolding machine comprising, a stationary frame, a rotatable cylinder, means for attaching a master-sheet to said cylinder, a roller co-operating with said cylinder and adapted to bring a moistened copy sheet into pressure contact with the master sheet on said cylinder, bearings supporting the ends of said roller and mounted on said frame for sliding movement towards or away from said cylinder, an oscillatable shaft carried by said frame, a lever fixed to said shaft, a detent for locating said lever in at least one angular position, crank arms fixed on said shaft, screw-threaded rods carried by said bearings and extending through openings in said crank arms, nuts screwed on said rods and co-operating with the sides of said crank arms nearest said bearings to enable individual adjustment of the pressures exerted on said cylinder by the ends of said roller.

5. A manifolding machine comprising, a stationary frame, a rotatable cylinder, means for attaching a master sheet to said cylinder, a roller co-operating with said cylinder and adapted to bring a moistened copy sheet into pressure contact with the master sheet on said cylinder, bearings supporting the ends of said roller and mounted on said frame for sliding movement towards or away from said cylinder, an oscillatable shaft carried by said frame, a lever fixed to said shaft, a spring-loaded member carried by said lever and adapted to co-operate with at least one recess in said frame to define the angular position of said shaft, crank arms fixed on said shaft, screw-threaded rods carried by said bearings and extending through openings in said crank arms, nuts screwed on said rods and co-operating with the sides of said crank arms nearest said bearings to enable individual adjustment of the pressures exerted on said cylinder by the ends of said roller.

6. A manifolding machine comprising, a stationary frame, a rotatable cylinder, means for attaching a master-sheet to said cylinder, a roller co-operating with said cylinder and adapted to bring a moistened copy sheet into pressure contact with the master sheet on said cylinder, a stationary moistening pad extending transversely of the machine, a pressing member adapted to press said copy sheet against said moistening pad, a container for said moistening pad, a rigid tie-bar connecting the sides of said frame and supporting said pad container, levers pivoted coaxially at opposite sides of said frame and carrying the ends of said pressing member, a tubular shaft mounted on said tie-bar, cams on said shaft each adapted on oscillation of the latter to raise or lower one of said levers, an arm on said shaft, a driving crank operatively connected to said cylinder, and co-operating with said arm at each revolution in a manner to oscillate said shaft.

7. A manifolding machine comprising, a stationary frame, a rotatable cylinder, means for

attaching a master-sheet to said cylinder, a roller co-operating with said cylinder and adapted to bring a moistened copy sheet into pressure contact with the master sheet on said cylinder, a stationary moistening pad extending transversely of the machine, a pressing member adapted to press said copy sheet against said moistening pad, a container for said moistening pad, a rigid tie-bar connecting the sides of said frame and supporting said pad container, levers pivoted coaxially at opposite sides of said frame and carrying the ends of said pressing member, a tubular shaft mounted on said tie-bar and cut away to al-

low engagement of the latter by said pad container, cams on said shaft each adapted on oscillation of the latter to raise or lower one of said levers, an arm on said shaft, a lateral projection on said arm, a driving crank operatively connected to said cylinder and having a cam surface adapted at each revolution to act on said projection in a manner to effect the raising of said pressing member, a spring-controlled detent associated with said crank and adapted to check said cylinder whilst said pressing member is raised.

10

FRANK RONALD FORD.
